DESIGN FOR A CAN OPENER

Henry J. Talge, Kansas City, Mo., assignor to
John C. Hockery, Foster L. Talge, and Henry
J. Talge, doing business as Rival Manufactur-
ing Company, Kansas City, Mo.

Application October 18, 1944, Serial No. 115,848

Term of patent 14 years

(Cl. D22—2)

To all whom it may concern:

Be it known that I, Henry J. Talge, a citizen of the United States, residing at Kansas City, Jackson County, State of Missouri, have invented a new, original, and ornamental Design for a Can Opener, of which the following is a specification, reference being had to the accompanying drawing, forming part thereof, in which

Fig. 1 is a side elevational view of a can opener embodying the new design,

Fig. 2 is a top plan of the can opener shown in Fig. 1,

Fig. 3 is a side elevational view taken from the opposite side from that shown in Fig. 1,

Fig. 4 is a front elevational view of the can opener shown in Fig. 1.

I claim:

The ornamental design for a can opener, substantially as shown.

HENRY J. TALGE.
